CLAIM

The ornamental design for a dove-shaped jewelry box, as shown and described.

DESCRIPTION

FIG. 1 is a perspective view of a dove-shaped jewelry box showing the new design.

FIG. 2 is a rear elevation view of the dove-shaped jewelry box.

FIG. 3 is a front elevation view of the dove-shaped jewelry box.

FIG. 4 is a bottom plan view of the dove-shaped jewelry box.

FIG. 5 is a right side elevation view of the dove-shaped jewelry box.

FIG. 6 is a left side elevation view of the dove-shaped jewelry box.

FIG. 7 is an enlarged partial view of the front bottom of the dove-shaped jewelry box.

FIG. 8 is an enlarged partial view of the rear bottom of the dove-shaped jewelry box.

FIG. 9 is an enlarged partial view of the right side bottom of the dove-shaped jewelry box.

FIG. 10 is an enlarged partial view of the left side bottom of the dove-shaped jewelry box; and,

FIG. 11 is an enlarged partial view of the front top of the dove-shaped jewelry box.

Broken lines depict portions of the dove-shaped jewelry box that form no part of the claimed design.
